UNITED STATES PATENT OFFICE.

LOUIS WILPUTTE, OF NEW ROCHELLE, NEW YORK.

COKE-OVEN.

1,213,938.

Specification of Letters Patent. Patented Jan. 30, 1917.

Application filed June 19, 1916. Serial No. 104,377.

To all whom it may concern:

Be it known that I, LOUIS WILPUTTE, a subject of the King of Great Britain, and a resident of New Rochelle, county of Westchester, and State of New York, have invented a certain new and useful Improvement in Coke-Ovens, of which the following is a true and exact description, reference being had to the accompanying drawings, which form a part thereof.

10 My present invention relates to oven structures such as retort coke ovens, and the general object of the invention is to improve the heating provisions of such ovens.

15 More specifically my invention relates to an oven structure having a heating wall formed with a plurality of vertical heating flues communicating at their upper ends through definitely restricted passages with a horizontal collecting and distributing 20 channel, and having gas supply nozzles or analogous regulating or controlling devices located at the lower ends of the vertical flues and accessible through the latter for adjustment, inspection or renewal; and the specific 25 object of my invention is to provide improved means for definitely restricting communication between the upper ends of the vertical flues and the horizontal passage.

30 In carrying out my invention I employ flue restricting parts which are hinge connected with the stationary portion of the oven structure at or adjacent the bottom wall of the corresponding horizontal passage, so that they may be easily swung out of their normal positions in which they restrict communication between the flues and the horizontal passage to facilitate inspection 35 or manipulation of the nozzles or analogous regulating devices at the bottom of the flues, and when this inspection or manipulation is completed may easily be returned into the exact normal position previously occupied by them.

40 The various features of novelty which characterize my invention are pointed out with particularity in the claims annexed to and forming a part of this specification.

45 For a better understanding of the invention, however, and the advantages possessed by it, reference should be had to the accompanying drawings and descriptive matter in which I have illustrated and described a preferred embodiment of my invention.

50 Of the drawings: Figure 1 is a partial sectional elevation of a retort coke oven,

the section being taken parallel to the length of the retorts and along the line 1—1 of Fig. 2; Fig. 2 is a partial section taken on the line 2—2 of Fig. 1; Fig. 3 is a view taken similarly to Fig. 2, but on a larger scale and with one of the flow restricting devices removed; Fig. 4 is a partial sectional plan taken on the line 4—4 of Fig. 1; and Fig. 5 is a perspective view of one of my movable flue restricting devices.

55 In the coke oven structure shown in the drawings, A represents the masonry coke oven structure proper and A' the parallel coke oven retorts formed therein. In the 60 heating wall between each adjacent pair of retorts A' are formed a plurality of vertical heating flues B which communicate at their upper ends through passages or necks B', with a horizontal collecting and distributing passage C as in the well known Otto-Hoffman type of flue arrangement. Communicating with the lower ends of the flues B are air supply passages B² and gas supply passages B³ which communicate at 65 their lower ends with the gas supply canal B⁴. Mounted in each passage B³ is a flow regulating nozzle D. Vertical passages F are formed in the upper portion of the oven structure leading from the horizontal passages C to the upper side of the oven structure. These passages are normally closed as by removable closures F'. The passages F are in axial alignment with the vertical 70 heating flues B and are provided to make it possible to inspect, adjust, remove or replace the nozzles D or analogous devices through the passages F and flues B when the closures F' are removed.

75 In so far as already described the coke oven structure illustrated embodies nothing peculiar to the present invention which is concerned with the means I am now about to describe for restricting communication between the different vertical flues B and the 80 horizontal passage C in normal operation.

85 In the preferred construction illustrated there are a pair of similar flow restricting parts E, proper at the upper end of each flue. The parts E which in practice are in effect fire clay bricks of special shape, each 90 comprises a flat rectangular body portion with a pair of trunnion or pintle extensions E' at one side edge. In the normal condition of the apparatus, the two members E 95 lie edge to edge in the same plane and are received in a recessed seat C' formed in the 100

95

100

105

110

bottom wall of the horizontal passage C and extend across the corresponding passage B'. Each seat C' is formed with an opposing pair of extensions C² at the ends of each side edge which receive and form open bearings for the corresponding trunnion or pin-like portions E'. The two plate like members E mounted in each seat C' are each formed with a notch E² in its free edge which, in the normal condition shown in

Fig. 1 and in the left hand portion of Fig. 2, registers with the corresponding notch in the coöperating member E to provide a port or passage of the proper size between the corresponding flue B and passage C.

When it is desired to inspect or manipulate one of the nozzles D, this may be readily accomplished as follows: First the closure F' for the upper end of the corresponding channel F is removed and then a poker-like tool passed down through the open channel F and the horizontal passage C and through the opening formed by the registering notches E² in the meeting edges of the corresponding pair of members E. The tool is then manipulated to swing the two members E into the positions occupied by them in the right hand portion of Fig. 2. The members E are then out of line with the

passage B' and give ample room for inspection or manipulation of the nozzle D or analogous device at the bottom of the corresponding flue B. After each inspection or manipulation is completed, the members E are swung back to the normal position shown at the left in Fig. 2. In this normal position, the cross sectional area of the passage formed by the notches E² is a fixed and definite quantity which is not disturbed or

affected by the movement of the members into and out of the dotted line position shown in Fig. 3 and in the right hand portion of Fig. 2.

The size of the opening formed by the two notches E² needs to be very definitely and precisely determined to insure the proper distribution of the heating gases among the different heating flues. In case the notches in the members E originally provided at the top of any flue B are not of the proper size, these members may be readily removed and replaced by others having notches E² of the proper size. If, as well may be the case, the passages F are too small to permit the withdrawal through them of the members E, the latter may be first moved up on to the upper surface proper of the bottom wall of the horizontal passage C and then moved lengthwise of the latter out of the oven through the opening in the side wall of the oven structure normally closed by the removable brick or door A¹⁰. Since in the ordinary adjustments of the members E between the positions shown in full and dotted lines in Figs.

2 and 3 but little force is required to move the members E, and the latter need not be lifted or firmly gripped by tongs, there is but little likelihood of breakage in making such adjustments.

My invention was primarily devised for the purpose of overcoming a difficulty of considerable importance which has been experienced with coke ovens of the general type illustrated, when an adjustable slide brick is employed at the top of each flue B to regulate the communication between the latter and the horizontal passage. While these slide bricks have been extensively used, and form effective means for regulating communication between the different vertical flues and the horizontal passage, their use is open to the serious objection that when it is necessary to inspect or manipulate a gas supply nozzle or the like at the bottom of the flue, it is necessary to move the slide brick to one side and after this has been done, there is nothing to fix with certainty that the slide brick will thereafter be returned to the former position, which in most cases had been arrived at as a result of careful observations and experiments. With my invention all difficulty of this sort is avoided.

While in accordance with the provisions of the statutes I have illustrated and described the best form of my invention now known to me, it will be apparent to those skilled in the art that changes can be made in the form of my invention without departing from its spirit, and that some features of my invention can be used without a corresponding use of other features of the invention.

Having now described my invention, what I claim as new and desire to secure by Letters Patent, is:

1. A coke oven structure formed with vertical heating flues and a horizontal passage to which the upper ends of said flues open, and in combination therewith members in hinged relation with said structure to swing into and out of a normal position in which they restrict communication between said flues and said passage.

2. A coke oven structure formed with vertical heating flues and a horizontal passage to which the upper ends of said flues open and with a recessed seat at the upper end of each flue, and in combination therewith flue restricting devices in hinged engagement with said structure and adapted to swing into and out of a normal position in which they are received in the corresponding seats.

3. A coke oven structure formed with vertical heating flues and a horizontal passage to which the upper ends of said flues open, and in combination therewith a pair of members hinge-connected to said structure

adjacent the upper end of each flue and adapted to be swung into and out of position in which they meet edge to edge and project across said flue.

5. A coke oven structure formed with vertical heating flues and a horizontal passage to which the upper ends of said flues open, and in combination therewith a pair of members hinge-connected to said structure 10 adjacent the upper end of each flue and adapted to be swung into and out of position in which they meet edge to edge and project across said flue, each member being formed with a notch in its edge which registers with a corresponding notch in the other when the members extend across the flue to form a part connecting the flue to said passage.

5. A coke oven structure formed with vertical heating flues and a horizontal passage 20 to which the upper ends of said flues open and being also formed with notches or recesses in said passage adjacent the upper

ends of said flue, and in combination therewith flow restricting devices formed with 25 pintle portions journaled in said notches to swing into and out of the position in which they extend across the corresponding flues.

6. A coke oven structure formed with vertical heating flues and a horizontal passage 30 to which the upper ends of said flues open and having recessed seats in the bottom wall of said passage one for each of 35 said flues, and in combination therewith flow restricting devices which normally are snugly received in said seats and extend across the flues, each of said devices being formed with an opposed pair of trunnion extensions and each seat being formed with offset portions in which said extensions are 40 journaled.

LOUIS WILPUTTE.
